Primary Examiner — John Windmuller*(74) Attorney, Agent, or Firm* — Aka Chan LLP(57) **CLAIM**

The ornamental design for an umbrella with solar panels, as shown and described.

DESCRIPTION

These applications are incorporated by reference along with U.S. patent application Ser. No. 29/461,658, filed Jul. 26, 2013.

FIG. 1 shows a perspective view of a design for an umbrella with solar panels.

FIG. 2 shows a top view of design; and,

FIG. 3 shows a side view of design.

The broken-lines features in the figures are for illustrative purposes only and form no part of the claimed design.
